HENRY D. JAMES, OF PITTSBURGH, PENNSYLVANIA, ASSIGNOR TO WESTINGHOUSE ELECTRIC AND MANUFACTURING COMPANY, A CORPORATION OF PENNSYLVANIA.

CONTROLLER FOR INDUCTION-MOTORS.

1,116,433.

Specification of Letters Patent. Patented Nov. 10, 1914.

Application filed September 19, 1910. Serial No. 582,658.

To all whom it may concern:

Be it known that I, HENRY D. JAMES, a citizen of the United States, and a resident of Pittsburgh, in the county of Allegheny and State of Pennsylvania, have invented a new and useful Improvement in Controllers for Induction-Motors, of which the following is a specification.

My invention relates to electric controllers 10 and particularly to controllers for induction motors having resistances in the secondary circuits thereof.

The object of my invention is to provide a controller of the character indicated for 15 manually removing resistance from the secondary circuit of an induction motor and automatically reinserting the same therein upon interruption of the primary circuit.

Figure 1 of the accompanying drawing is 20 a diagrammatic view of a system embodying a controller constructed in accordance with the present invention and Fig. 2 is a similar view of a system embodying a modification of the controller shown in Fig. 1.

25 The system shown in Fig. 1 comprises an induction motor 1, the primary winding of which is adapted to be connected to a suitable supply circuit 2-3-4 by means of a multiple pole switch 5; fuses 6, or other 30 suitable protecting devices, being preferably interposed between the switch and the motor. The secondary circuit of the motor includes a plurality of resistors 8, 9 and 10, suitable points of subdivision of which are 35 connected to the stationary contact terminals 11 of a manually operated controlling device 12, the said contact terminals being arranged in groups which are associated, respectively, with the resistors 8, 9 and 10.

40 The controller has a multiple-arm rotatable member 13, that is normally retained in the position shown by means of a spring 14, the extremities of the arms of said member being adapted to engage the stationary contact terminals 11. When the rotatable member 13 occupies the position shown, the resistors 8, 9 and 10 are entirely included in the secondary circuit of the motor, but, as the said member is moved in a clockwise direction, sections of the resistors are successively short-circuited and are thereby, in effect, removed from the secondary circuit. One arm 15 of the rotatable member 13 is provided with a lug 16 that is adapted to be 45 engaged by a latch 17 when the rotatable

member occupies its final position, provided the switch 5 is closed; the latch 17 being here shown as a bell-crank lever, one end of which is connected, by means of a rod 18, to a second bell-crank lever 19 that is actuated to raise the rod 18 when the switch 5 is closed. A convenient means for actuating the bell-crank lever 19, when the switch 5 is closed, consists of a rod 20 that is moved into engagement with one arm of the said lever by the closing of the switch. In order to start the motor, the switch is first closed in order to connect the primary winding of the motor to the supply circuit. Upon closing the switch 5, members 17, 18, 19 and 20 are actuated to move one end of the latch 17 into the path of movement of the lug 16 of the arm 15. In order to increase the speed of the motor, the rotatable member 13 of the controller 12 is rotated in a clockwise direction, to gradually remove the resistors 8, 9 and 10 from the secondary circuit of the motor. When the movable member 13 reaches its final position, the resistors 8, 9 and 10 are entirely removed from the secondary circuit of the motor and the lug 16 is engaged by the latch 17. If it is desired to stop the motor, the switch 5 is opened, whereupon the latch 17 releases the lug 16 and the spring 14 returns the rotatable member 13 to its initial position to include all of the resistors 8, 9 and 10 in the secondary circuit of the motor. Thus, the present controller insures that when the motor is again started, the resistances 8, 9 and 10 will be included in the secondary circuit of the motor, and, consequently, there will be no danger of supplying an excessive current to the motor.

Instead of the switch 5 of Fig. 1, a multiple pole circuit breaker 22 may be employed for governing the connections of the primary winding to the supply circuit, as shown in Fig. 2, and the circuit breaker may be adapted to be opened automatically, in the usual manner, when the motor is overloaded, or upon the occurrence of other predetermined abnormal conditions. The remainder of the system is substantially the same as that shown in Fig. 1, the latch 17 being interposed in the path of movement of the lug 16 only when the circuit breaker is closed, and being adapted to automatically release the same when the circuit breaker is opened.

I claim as my invention:

1. The combination with an alternating current induction motor having primary and secondary windings, and resistors associated with the said secondary winding, of a regulating device for said resistors having a movable member biased toward its initial position, a latch for retaining the said member in its final position, a switch in circuit with the primary winding of the motor, means for operatively connecting the latch to the said switch comprising a spring that resiliently applies pressure to the latch when the switch is closed, and that permits the latch to release the movable member of the regulating device when the switch is opened.
2. The combination with a regulating de-

vice having a movable member biased toward its initial position, of a switch, a latch, an operative connection between the switch and the latch comprising resilient means for causing the latch to retain the movable member of the regulating device in its final position when the switch is closed, and for causing the latch to release the said member when the switch is opened.

In testimony whereof, I have hereunto subscribed my name this 12th day of Sept., 1910.

HENRY D. JAMES.
